UNITED STATES PATENT OFFICE.

HERMAN STOLL, OF DETROIT, MICHIGAN, ASSIGNOR TO GENERAL MOTORS CORPORATION, OF DETROIT, MICHIGAN, A CORPORATION OF DELAWARE.

PISTON-RING GROOVE.

Application filed August 31, 1925. Serial No. 53,601.

This invention has to do with pistons, such as are used in internal combustion engines, which are customarily provided with grooves in which the usual piston rings are seated. These grooves are formed in the piston by applying thereto a cutting tool having a flat cutting edge. After some use the cutting edge becomes worn at the corners, resulting in the production of a groove the bottom of which is slightly concave. When the piston ring which customarily has a flat rear wall, is now seated in the groove, it engages at the high points, that is, at the sides of the groove only, and, as a result, projects further beyond the surface of the piston than is desired.

To avoid this inaccuracy I have preferred to form my groove with a bottom which is slightly higher at the center than at the sides. While this may be accomplished by using a tool having a cutting edge of various configurations, I have preferred to use one the cutting edge of which is concave. With this construction the corners of the tool may wear to a considerable degree and yet produce a groove the bottom of which is higher at the center than at the sides. The reduction in depth of the groove at the sides, incident to wearing of the tool, will not affect the extent of projection of the rings beyond the sides of the piston.

In the drawings Figure 1 is a side elevation of a piston of conventional type, the piston rings being shown in section;

Figure 2 is an enlarged view of a portion of the construction shown in Figure 1.

Reference character 2 indicates a piston of conventional type. The ring grooves are indicated by reference character 4 and the rings by the reference character 6. The rings are illustrated as rectangular in cross section, but this is not essential and any other type of ring may be substituted for that shown.

My invention resides in so forming the surfaces constituting the backs of the rings

and the bottoms of the grooves that they will contact only at the centers of the grooves. This may be done in a number of ways. I have chosen to illustrate the bottoms of the grooves as of convex contour as shown at 10, so that the contact between the back of the ring and the bottom of the groove will be substantially along a line extending around the piston and midway of the width of the groove. It is obvious that it is not essential that the bottom of the groove be convex so long as the central portion of the bottom of the groove be higher than the side portions.

As previously pointed out, with this construction the extent of projection of the piston rings from the sides of the pistons is maintained constant despite lack of exact uniformity in making the cut at the sides of the grooves.

What I claim and desire to protect by Letters Patent is:

1. A combination of a piston having a groove therein having parallel sides to permit ready removal of the cutting tool, a ring in the groove, the bottom of the ring and the bottom of the groove being so formed as to contact only at substantially the center of the groove, there being clearance between the back of the ring and the bottom of the groove at the sides of the latter.

2. A combination of a piston having a groove therein having parallel sides to permit ready removal of the cutting tool, the bottom of the groove being convex and the ring having a rear wall adapted to engage the bottom of the groove at the center only.

3. A combination of a piston having a groove therein having parallel sides to permit ready removal of the cutting tool, the bottom of the groove being convex and a ring having a flat rear wall adapted to engage the bottom of the groove.

In testimony whereof I affix my signature.

HERMAN STOLL.
